UNITED STATES PATENT OFFICE.

JAY SIMONS, OF HOMESTEAD, FLORIDA.

DISHWASHER.

Application filed May 10, 1921, Serial No. 468,208. Renewed December 19, 1924.

To all whom it may concern:

Be it known that I, JAY SIMONS, a citizen of the United States, residing at Homestead, in the county of Dade and State of Florida, have invented certain new and useful Improvements in Dishwashers; and I do hereby declare the following to be a full, clear, and exact description of the invention, such as will enable others skilled in the art to which it appertains to make and use the same.

The present invention relates to dish washers, and aims to provide a novel and improved device of that kind which is useful for washing dishes, cooking utensils, chinaware, silverware, and the like, and which is sanitary and efficient in use.

An object of the invention is the provision of a washing machine having novel means for directly water and air against the dishes and other articles with considerable force, for washing, rinsing, drying and cooling the dishes in succession, all in one continuous operation.

Another object is the provision of a novel rotary fan with means for supplying water to the blades, whereby such blades will break up the water into a fine spray and direct such spray of water against the dishes with considerable force, for softening and loosening the accumulations and foreign matter from the dishes.

A further object is the provision in connection with a rotary fan or spraying device, of novel means for supplying water thereto and controlling the flow thereof.

A further object is the provision of novel means for mounting the holders or racks for the dishes and other articles in the casing, for the movement of the dishes and effective spraying of the water against them, so that the water and also the air are directed against all sides of the dishes for thoroughly cleaning them.

A still further object is the provision of racks or holders of novel form for holding dishes, knives, forks, spoons, drinking glasses, and the like.

Another object is the provision of a novel actuating mechanism for the fan or spraying device and the racks or holders.

The invention has for a further object the provision of such a washing machine comprising a novel arrangement and assemblage of the component elements, in order to provide for the efficient operation

of the machine and to enhance the utility thereof.

With the foregoing and other objects in view, which will be apparent as the invention is more fully understood, the invention resides in the construction and arrangement of parts as hereinafter described and claimed, it being understood that changes can be made within the scope of what is claimed, without departing from the spirit of the invention.

The invention is illustrated in the accompanying drawings, wherein:

Figure 1 is a plan view of the machine.

Fig. 2 is a vertical section thereof taken on the line 2—2 of Fig. 1, portions being shown in elevation.

Fig. 3 is an enlarged plan view of the valve tube adjuster in releasing position as when opening or closing the lid or cover.

Fig. 4 is a section on the line 4—4 of Fig. 3.

Fig. 5 is a perspective view of the rack or holder for knives, forks, and spoons.

Fig. 6 is a plan view of the rack or holder for plates, saucers and similar dishes.

Fig. 7 is a plan view of the rack or holder for drinking glasses or tumblers.

Fig. 8 is an enlarged vertical sectional detail on the line 8—8 of Fig. 1.

Fig. 9 is a fragmentary elevation showing a modification.

Fig. 10 is a section on the line 10—10 of Fig. 2.

The machine comprises a suitable casing 11, preferably of sheet metal, having the inclined bottom 12 which slopes to a drain faucet 12^a, whereby the water will drain readily from the casing when said faucet is open. The casing 11 is mounted on a suitable base 13 which can have legs 14 to support it on the floor or other surface. The casing has a lid or cover 15 hinged to the rim of the casing 11, as at 16, so that said lid can be swung open upwardly, and the lid, when closed, is fastened down by suitable catches 17.

Disposed within the casing at different points around the central vertical axis of the casing are a plurality of upstanding rock shafts 18 (four as shown) which have their lower terminals journaled in suitable bearings 19 in the bottom 12 of the casing and base 13. Said shafts 18 are thus supported in upright position within the casing, and their upper terminals are journaled

within a spider 20 disposed underneath the lid 15 and also preferably hinged, as at 16, in order that when the lid is swung open, said spider can also be swung upwardly off 5 of the upper ends of the shafts 18. The spider or bearing member 20 has apertures 21 receiving the upper ends of said shafts when the spider is swung down and seated on the rim of the casing, in order to hold 10 said shafts in vertical position. In order that all of the shafts 18 will be actuated in unison, sprocket wheels 22 are secured thereon near the bottom of the casing 11, and an endless sprocket chain 23 passes around said 15 sprocket wheels, so that the actuation of any one shaft 18 will similarly actuate the others.

The shafts 18 are for the purpose of supporting the racks or holders for the dishes 20 and other articles to be washed, and suitable racks or holders are provided, including one or more racks 24 for plates, saucers, and other dishes, one or more racks 25 for drinking glasses or tumblers, and one or more 25 racks 26 for knives, forks, spoons and the like. These and similar racks are slipped down on the shafts 18, when the lid 15 and the spider 20 are raised, and said racks are supported in the desired vertical positions 30 by spacing sleeves 27 of different lengths fitted on said shafts below and between the racks. The shafts 18 are of square or non-circular cross section from the sprocket wheels 22 to their upper terminals and the 35 sleeves 27 are of similar cross section. The racks 24, 25 and 26 will be described in detail hereinafter.

The fan or spraying device comprises a vertical tubular shaft 28 having its lower 40 terminal portion journaled in suitable bearings 29 provided in the casing bottom and base 13 and gear frame 13^a of the base, whereby to support said shaft 28 for free rotation. The fan blades 30 are secured to the 45 shaft 28 in any suitable manner and extend radially therefrom in vertically spaced positions. The blades 30 have flanges 31 at their upper and lower edges extending forwardly, to prevent the water from spreading too far 50 so as to pass off of the upper and lower edges of the blades, and to compel the water to be thrown outwardly away from the shaft 28 when said shaft is rotated at a high speed. The shaft 28 has water nozzles 32 extending 55 in front of the blades 30 for delivering the water to the front sides of the blades, so as to break up the streams or jets of water into a fine spray and to discharge the water from the blades in fan-shaped streams when the 60 fan is rotated with sufficient velocity. The fan-shaped streams are disposed vertically, and being distributed on different sides of the shaft 28 and in different vertical positions will deliver the water from the center 65 of the casing throughout the entire space in

which the dish racks or holders may be located on the shafts 18. The lid 15 and spider 20 have central openings 33 for receiving the upper terminal of the shaft 28 in order to support said shaft in proper vertical position 70 when in operation. It is also preferable to provide a cylindrical screen 34 of coarse or large mesh surrounding the fan, to prevent the possible contact of the dishes with the fan blades as would be apt to break the 75 dishes or cause other damage. The screen 34 is mounted on and rises from the bottom 12 of the casing and thereby serves as a guard for the fan.

The actuating mechanism for the fan 80 shaft 28 and rock shafts or posts 18 includes a gear pinion 35 secured on the lower terminal of the shaft 28 and meshing with a gear wheel 36 mounted on a short vertical shaft 37 journaled in the frame 13^a 85 and base 13. A bevel gear 38 secured to the gear wheel 36 meshes with the bevel gear 39 secured on a horizontal shaft 40 journaled in the frame 13^a, and said shaft 40 is connected by bevel gears 41 with the 90 lower end of a vertical shaft 42 journaled for rotation in an extension 43 of the frame 13^a which projects upwardly at one side of the casing. A bevel pinion 44 is secured to the upper end of the shaft 42, and meshes 95 with a bevel gear wheel 45 secured to a drive shaft 46 journaled in the upper portion of the extension 43 and having a crank handle 47 for manual operation. The crank 47 in being rotated will drive the shaft 28 100 at a high speed of rotation, such as is necessary to take advantage of centrifugal action for spraying the water from the fan. The lower end of one of the shafts 18 is connected by bevel gears 48 with a short 105 horizontal rock shaft 49 journaled in the base 13 and having a crank 50 connected by a pitman 51 with a gear wheel 52 mounted in the frame 13^a and meshing with a gear pinion 53 secured on the shaft 40. 110 Thus, when the fan is rotated at a high speed, the rotation of the gear wheel 52 at a much slower speed, will oscillate the shaft 49, thereby slowing oscillating shafts 115 18 and turning racks 24, 25 and 26 back and forth through an angle of about ninety degrees so that the water will be directed against the dishes and other articles on all sides thereof.

One or more oil cups 54 can be provided 120 for the bearings and other means afforded for lubrication.

The flow of water into and through the nozzles 32 is controlled by a valve tube 55 fitted for longitudinal sliding movement in the shaft 28 and having apertures 56 to register with the nozzles for the flow of water from within the tube 55 through the nozzles to the fan blades 30. A feather or spline 57 is used to compel the tube 55 to rotate 130

- with the shaft 28, but permits the tube 55 to be raised and lowered for increasing or decreasing the discharge of water, as may be desired.
- 5 The water is supplied from a tank or reservoir 58 having feet 59 seated on seats 60 on the lid 15 and set screws 61 are carried by the seats 60 for holding the feet 59 thereon to prevent the tank from being 10 displaced, although said tank can be readily removed by loosening the set screws 61. A bowl 62 is carried by the tank at a lower level than the bottom of the tank and at one side thereof, to be disposed above the shaft 28 and tube 55, and said bowl has a depending discharge spout 63 on which a coupling member 64 is swivelled to connect with the upper end of the valve tube 55. The lower end of the coupling member 64 is tapered, as at 65, to fit snugly within upper tapered end of the bore of the tube 55, and the telescoped ends of the spout 63 and member 64 have the outturned and inturned flanges 66 and 67, respectively, between 15 which packing 68 is disposed to prevent leakage. The member 64 is also slidable on the spout 63 and is yieldingly depressed by a coiled expansion spring 69 surrounding the spout and confined between the member 20 64 and bottom of the bowl 62. Thus, when the lid 15 is down in place and the tank 58 on the lid, the member 64 will fit down within upper end of the tube 55, under the tension of the spring 69, to prevent leakage 25 between the member 64 and tube 55, and said member will rotate with the tube around the spout 63. The member 64 can also move up and down with the valve tube 55.
- 30 40 The tank 58 has a faucet 70 for the discharge of water from the tank into the bowl 62 into which the faucet extends, and the discharge of water is controlled by a spigot or valve 71. The bowl 62 is kept filled with water up to a predetermined level by means 45 of a float 72 in the bowl having a valve 73 to seat upwardly against the faucet 70, as seen in Fig. 8, to prevent the further entrance of water into the bowl, until the water 50 level is lowered and the float is moved downwardly away from the faucet.
- The adjusting means for the valve tube 55 includes a pair of levers 74, and a collar 75 fitted in an annular groove 76 in the upper 55 protruding end portion of the tube 55, said collar having opposite apertures 77 for receiving lugs 78 projecting from the levers near one end thereof. Said levers are provided between their ends with fulcrum lugs 79 entering a peripheral groove 80 in a fulcrum member and cam 81, which is of elliptical form and disposed between said levers at one side of the tube 55. The member 81 is mounted for rotation on an upstanding post 82 secured on the lid, and a spring 85

connects the levers 74 to swing them toward one another when the member 81 is turned to the position as seen in Fig. 1, with its major axis midway between the levers 74, whereby the lugs 78 engage in the apertures 77. Those ends of the levers opposite to the lugs 78 have overlapping and hingedly connected ears 86 apertured to receive a screw 87, which has the lower end pivoted, as at 88, or otherwise attached to the lid. A nut 89 is threaded on said screw and the corresponding ends of the levers bear upwardly against said nut. Thus, when the member 81 is turned to permit the levers 74 to swing toward one another and the lugs 78 to enter the apertures 77, the non-rotatable collar 75 is supported from the levers, and the tube 55 is therefore suspended from the collar, thereby tending to swing the levers 74 on the lugs 79 to raise the opposite ends of the levers. By adjusting the nut 89, the levers 74 are swung to either raise or lower the tube 55 for increasing or decreasing the flow of water from the valve tube through the nozzles 32. The position of the valve tube is indicated by a graduated post or scale 90 rising from the lid 15 and cooperable with one of the levers 74, so that said levers in being swung to adjust the valve tube 55 to different vertical positions will indicate on the scale the position of the tube so that the operator may know at what rate the water is being delivered to the fan. The member 81 not only forms a bearing for the fulcrum lugs 79, but also serves to separate the levers 100 74, when the member 81 is turned to the position as seen in Fig. 3. This removes the lugs 78 from the collar 75, for the purpose of raising the lid 15. The levers 74 have notches 84 in which the ends of the member 105 81 engage to hold the levers separated until the lid is again closed. The member 81 has finger pieces 83 thereon for convenience in turning said member.

The rack or holder for knives, forks and spoons comprises a sleeve 100 of square cross section to slip down on any one of the shafts 18, and arms extending from said sleeve. Each of said arms includes a pair of wires 101 secured at their inner ends to the sleeve 100 and provided with depending kinks 102 forming notches or seats in which the knives, forks and spoons can be placed. The wires 101 of each arm are twisted together at the outer end of the arm to form a supporting leg 103 having a foot 104 to rest on a table or other surface, and the arms are preferably arranged at an obtuse angle with one another so that the legs 103 and sleeve 100 form a three-point support to prevent the 115 rack from tilting or falling over while being filled when resting on a table or other support.

The plate and saucer rack or holder 24 also has a sleeve 105 similar to the sleeve 100 120

- to fit down on the shafts 18 and arms extending from said sleeve and also arranged at an angle with one another. Each arm includes a pair of upper wires 106 having 5 pairs of oblique kinks 107 for receiving the opposite edges of the plates or saucers, as seen in Fig. 6, and a lower wire 108 having kinks 109 for receiving the lower edges of the plates or saucers, thereby holding them 10 in place. The outer ends of each set of wires 106 and 108 also have a supporting leg 110 similar to the legs 103 for supporting the rack on a table or other surface, while being filled or emptied.

15 The rack or holder 25 for drinking tumblers or glasses has a sleeve 111 to fit on the shafts 18 and arms comprising the wires 112 twisted together, as at 113, to form the loops or receptacles 114 for receiving the 20 tumblers or glasses which are usually tapered. The forward loops 114 are larger than the rear ones for the convenient insertion of the tumblers and to snugly hold them in place in the loops and to prevent the tumblers passing on backwardly out of the loops. Each arm has a leg 116 at its outer 25 end similar to the legs 103 of the rack 26, and a retaining wire or member 117 has an eye 118 at one end engaging the corresponding leg 116 to hingedly connect said member 117 to the outer end of the corresponding arm and said member 117 has the offset portions 119 to enter the mouths of the tumblers 115 when the member 117 is swung inwardly 30 adjacent to the arm after the tumblers are inserted. The free end of each member 117 has a hook 130 to engage the front wires 112 of the arm and thus hold said member in place to prevent the tumblers sliding forwardly out of the loops or receptacles 114.

35 Any number and variety of the racks or holders can be used, having the sleeves to be fitted down on the shafts 18 when the lid 15 and spider 20 are raised, and the spacing 40 sleeves 27 can be used for spacing the racks apart and supporting them in different vertical positions as may be desired. The racks can also be placed on the shafts in different positions for the most effective delivery 45 of the water and air from the fan against the dishes or other articles while being oscillated with said shafts.

50 In using the machine, the dishes and other articles are placed within the racks and such racks are then placed on the rock shafts or posts 18 when the lid 15 and spider 20 are in raised position, suitable spacing sleeves 27 also being fitted on said shafts for supporting said racks, to suitably arrange the 55 racks and dishes around the central fan. After the racks and dishes are placed within the casing, the spider 20 is swung down on the casing and the upper ends of the shaft 60 28 and dish rack shafts 18 inserted in the respective apertures in said spider. The lid 65

15 is now swung down on the spider, and fastened by the catches 17. The member 81 is then turned to enable the lugs 78 to move into the apertures 77 of the collar 75. The tank 58 is then filled with water of 70 suitable temperature, and is supplied with soap from a liquid soap cup 99 attached to the tank, a valve 98 controlling the flow of soap from the cup 99 into the tank. The water flows from the tank through the faucet 70, when the spigot 71 is opened, into the bowl 62 and down through the spout 63 and coupling member 64 into the valve tube 55. The coupling member 64 seats snugly within the upper end of said tube 65. The actuating mechanism is now driven whereby to 80 rotate the fan shaft 28 and to oscillate the shafts 18. Then when the fan is rotating at high speed, say between 1500 and 2000 revolutions per minute, and the water is admitted to the bowl 62 from the tank 58, the nut 89 is turned so as to move the valve tube 55 and bring the apertures 56 partially into registration with the nozzles 32, so that the water is discharged in jets in front of the 90 fan blades 50. The water in being struck by the blades will break up into a fine spray, and the centrifugal action will throw the water or spray radially from the shaft 28 against the dishes and articles supported 95 from the shafts 18. The water is thus directed with considerable force against the dishes, for loosening the foreign matter therefrom, and cleaning the articles. The racks being oscillated slowly during the operation, will present the different sides of the objects to the water sprays, so as to dislodge the foreign matter from the dishes as the racks can be arranged on the shafts 18 so that oscillation of the racks will present the opposite sides of the dishes to the water sprayed against them. The drain faucet 124 is kept open, so that the water dripping from the dishes and running down the sides of the casing can drain out, thereby 100 cleaning the casing at the same time. The valve tube 55 is kept full of water during the washing action, inasmuch as the valve 72 will maintain the water level in the bowl 62, the flow of the water from the tank 58 only being shut off when the water level rises in the bowl to seat the valve 73 of said 105 float against the faucet 72.

110 After the dishes have been washed with hot water, they can be rinsed, by pouring fresh hot water in the tank 58 and shutting off the supply of soap by closing the valve 98. The clear water is then sprayed against the dishes and will rinse same thoroughly, as well as rinsing the interior of the casing, so that the machine is self-cleaning, without 115 the necessity for stopping to drain out the water.

120 To dry the dishes, the levers 74 are first disconnected from the valve tube 55, by turn- 125

130

ing the member 81 to separate said levers, as seen in Fig. 3, thereby removing the lugs 78 from the collar 75. The lid 15 is now raised to open position, and by continuing the rotation of the fan, air is delivered from the fan to the dishes, thereby evaporating the moisture therefrom. This action of the air can also be used, if continued, for cooling the dishes should they be too hot to handle.

10 Then, by raising the spider 20, the racks can be readily lifted off the shafts 18 for removing the dishes.

The dishes are placed on the racks so as to be self-draining, to avoid the accumulation of water in the dishes, and the racks are preferably made of such material or are covered or coated to prevent the scratching of silverware, nicking of dishes, and other injuries to the articles.

20 The oscillation of the dish racks during the cleansing action, will cause the water to be directed against the dishes from different angles, thereby facilitating the loosening of matter clinging to the dishes. The machine is economical in the consumption of water and soap, and is also sanitary.

The actuating mechanism can be power-driven from any suitable source of power. Thus, as seen in Fig. 9, a pulley wheel 41' is 30 mounted loosely on the shaft 40' of the actuating gearing mounted in the base frame 13' and is connected to said shaft by means of a suitable clutch 42' operated by a suitable hand lever 47'. Thus, by swinging the hand lever 47', the clutch can be opened and closed for stopping and starting the machine at will.

Having thus described the invention, what is claimed as new is:—

40 1. A washing machine comprising a casing, a central water spraying fan within said casing, upstanding shafts within said casing at different sides of said fan, article racks fitted removably on said shafts, means for supporting said racks at different vertical positions on said shafts, and means for actuating said fan and said shafts for changing the positions of said racks during the operation of the fan.

50 2. A washing machine comprising a casing, a central water spraying fan within said casing, upstanding shafts within said casing at different sides of said fan, article racks fitted down on said shafts, and means for actuating said shafts for changing the positions of said racks.

60 3. A washing machine comprising a casing having a bottom and base, a fan within the casing having a vertical shaft, another vertical shaft within the casing, the lower terminals of said shafts being journaled in said bottom and base, an article rack fitted down on the second named shaft, means connected to the lower terminal portions of said shafts for actuating them, and a member

removably seated on the casing and having means for receiving the upper terminals of said shafts.

4. A washing machine comprising a casing having a bottom and base, an upstanding shaft having its lower terminal journaled in said bottom and base, article racks having sleeves fitted removably down on said shaft and means for supporting said racks in different positions, means connected to the lower terminal portion of said shaft for actuating it to change the position of said racks, and spraying means within the casing for directing water against articles held by said racks.

5. A water spraying fan having blades, and means for supplying water in front of said blades including nozzles extending to the front sides of the blades.

6. A washing machine comprising a rotary water spraying fan having a shaft and blades, and means for supplying water from within said shaft in front of said blades.

7. A washing machine comprising a rotary water spraying fan having a tubular shaft and blades carried by said shaft, water discharge nozzles extending from the shaft in front of the blades, and means for supplying water into said shaft to discharge through said nozzles.

8. A washing machine comprising a rotary water spraying device having a tubular shaft with water discharging means, a valve tube slidable in said shaft for controlling the discharge of water, means for rotating said shaft, and means for adjusting said tube to control the discharge of water.

9. A washing machine comprising a casing having a bottom and base, an upstanding tubular shaft having its lower terminal portion journaled for rotation in said bottom and base, said shaft having means for the discharge and spraying of water within said casing, a valve tube fitted within said shaft and adjusted vertically for controlling the discharge of water, means for delivering water downwardly into said tube, and means connected to the upper end portion of said tube for adjusting it vertically.

10. A washing machine comprising a casing, a lid for the casing, a tubular shaft mounted in the casing having water discharging and spraying means, a valve tube slidable in said shaft for controlling the discharge of water, means above said lid for delivering water downwardly into said tube, and means mounted on said lid and having a detachable connection with the upper end portion of said tube for adjusting the tube in said shaft and to be disconnected from the tube for raising the lid.

11. A washing machine comprising a casing, a lid for the casing, spraying means within the casing including a tube for receiving water, and means supported by the lid

- for supplying water having a detachable slip connection with said tube.
12. A washing machine comprising a casing, a lid for the casing, spraying means within the casing including a vertically adjustable water receiving tube, means carried by the lid for supplying water including a spout, and means for the detachable connection of said spout and tube including a spring-pressed coupling member slidably engaging one of them and having a slip connection with the other.
13. A washing machine comprising spraying means including a water receiving tube, a water supply tank, a bowl having a spout for connection with said tube, the tank having a faucet to deliver the water into said bowl, and a float in the bowl having a valve portion to seat against said faucet when the bowl is filled up to a predetermined level.
14. A washing machine comprising a casing, a lid for the casing, spraying means within the casing including a water receiving tube, a water supplying bowl supported above the lid and having a depending spout, and a spring-depressed coupling member mounted on the spout for turning and vertical movements and having a slip connection with the upper end of said tube.
15. An article rack for a dish washing machine of the kind described, comprising a sleeve to fit on a shaft having arms extending therefrom at an angle with one another, said arms being formed of wires and having bent portions for holding the articles, and said arms having legs at their outer ends to seat on a surface with said sleeve when filling or emptying the rack.
- In testimony whereof I have signed my name to this specification in the presence of two subscribing witnesses.
